CLAIM

The ornamental design for a table lamp, as shown and described.

DESCRIPTION

FIG. 1 is a front, left, top isometric view of the table lamp; FIG. 2 is a front, left, bottom isometric view of the table lamp;

FIG. 3 is a front elevation view of the table lamp;

FIG. 4 is a back elevation view of the table lamp;

FIG. 5 is a left side elevation view of the table lamp;

FIG. 6 is a right side elevation view of the table lamp;

FIG. 7 is a top plan view of the table lamp; and,

FIG. 8 is a bottom plan view of the table lamp.

The broken lines in the figures show portions of the table lamp that form no part of the claimed design.
